UNITED STATES PATENT OFFICE.

MILES E. MARSH, OF OKLAHOMA CITY, OKLAHOMA.

INTERCHANGEABLE HANGING PRICE TAG.

Application filed December 14, 1922. Serial No. 606,974.

This invention has for its object to provide a hanging price tag including a clamp for attaching the tag to the edge of a display shelf or such other place as may be used for displaying goods, a chain or other suspender of suitable length attached to said clamp by means of a clip stamped from the front face of said clamp, an interchangeable price card container and a set of suitably stamped cards 10 with words and numerals for a great variety of prices and combinations.

Ordinarily the price tags in use are made up of loose parts which are easily disarranged, become misplaced, do not positively indicate the goods whose price is wanted and are otherwise unsatisfactory.

Another object of my invention is to provide an interchangeable hanging price tag whose position is positively fixed directly in 20 front of the articles whose prices are to be indicated.

Another object of my invention is to provide an interchangeable hanging price card container so constructed as to hold any and 25 all price cards positively in place, prevent the said container being moved laterally or facing its back to the front without eventually returning to its intended position.

Other objects have to do with the detailed 30 construction of the interchangeable hanging price tag as will hereafter more fully appear.

My invention is illustrated in the accompanying drawings, wherein—

Figure 1 is a front view pictorially illustrating the combination of the various parts;

Figure 2 illustrates one of the many price cards;

Figure 3 is a vertical sectional view taken 40 along a center-line of the combined parts.

Figure 4 is a horizontal sectional view of the card container.

The same reference characters indicate the same parts in all the figures.

In the drawings 10 represents the shelf clamp made of sheet metal, or other suitable material, having at its lower front edge a 45 spring clip 11 punched from the hole 12 over

which is hooked the suspender 13 which may be a chain or other means of suspending the 50 interchangeable price card container 16. The said suspender 13 having lateral width, being hooked over clip 11 at 14 and into the slotted hole 17 of the said interchangeable price card container 16 at 15 always positions 55 the price tag in a vertical plane, prevents the said price tag from turning so that its back is never to the front, and at the same time permits the same price tag to be lifted or moved laterally in removing articles from 60 the shelf behind the said price tag. With this arrangement, should the position of the said price tag be disturbed, it will always, of its own accord, return to its original position. The length of the suspender 13 may be varied 65 to fit shelves of varying heights or where conditions demand any such change.

The interchangeable price tag container 16 may be of sheet metal or other suitable material, stamped out in such a manner as to form 70 beveled edges, thus adding to its finished appearance and causing it to appear thicker than a cross-section would indicate. Along the lower edge of the said price tag container 16 clips 18 are formed from the holes punched 75 through the said container 16, the purpose of these clips being to hold the price cards 20 rigidly in place. It is to be understood that the figures or words on the said price cards 20 and 21 and the number of the said clips 80 18 as shown in Figure 1 and Figure 2 are here used for illustrative purposes only and that the actual number of such clips 18 may be varied to suit the purpose for which the price tag is intended. Similar though slightly 85 shorter clips 19 are formed at the ends of the said card container 16 for the purpose of preventing any lateral motion of the said price cards 20. Near the top of the said card container 16 is formed a semi-cylindrical corrugation 22 for the purpose of preventing the said price cards 20 from being moved upward 90 at any ordinary movement of the said container. Thus it will be seen that the individual cards forming any combination for 95 pricing purposes are held rigidly in place

against any disturbance except when purposely removed for a new pricing arrangement.

Having described my invention what I claim is:

In combination with a clamp, a suspender and an interchangeable hanging price tag container having clips horizontally disposed along its lower edge, clips vertically disposed

at its ends, and a semi-cylindrical corrugation along its upper edge, said clips and corrugation firmly holding in place previously numbered and lettered cards, and preventing said cards from being disturbed by wind or careless handling.

In testimony whereof I hereunto affix my signature.

MILES E. MARSH.
